CLAIM

I claim the ornamental design for a fluid pump apparatus, as shown and described.

DESCRIPTION

FIG. 1 is rear view of a fluid pump apparatus showing my new design;

FIG. 2 is a front view thereof;

FIG. 3 is a top view thereof;

FIG. 4 is a bottom view thereof;

FIG. 5 is a first side view thereof;

FIG. 6 is a second side view thereof;

FIG. 7 is an upper perspective view thereof;

FIG. 8 is a side view thereof on a reduced scale and in use with a fluid tank, hose, and spray nozzle; and,

FIG. 9 is a side view thereof on a reduced scale and in use with a hose and spray nozzle.

Portions of the drawings shown in broken lines form no part of the claimed design.
